United States Patent Office

Des. 184,757
Patented Mar. 31, 1959

184,757

COMBINED STEAM AND SPRAY IRON OR SIMILAR ARTICLE

Walter E. Moore, Trumbull, Rudolph H. Koepf, Orange,
and Paul O. Rawson, Jr., Trumbull, Conn., assignors
to General Electric Company, a corporation of New
York

Application July 1, 1957, Serial No. 46,795

Term of patent 14 years

(Cl. D49—6)

Fig. 1

Des. 184,757
PAGE 2

Fig. 1 is a perspective view looking downwardly at the front of the combined steam and spray iron;

Fig. 2 is a perspective view looking downwardly at the rear of the iron;

Fig. 3 is a side elevation; and

Fig. 4 is a top plan view.

We claim:

The ornamental design for a combined steam and spray iron or similar article, substantially as shown.
